UNITED STATES PATENT OFFICE.

JOHN ALFRED PRESTWICH, OF LONDON, ENGLAND.

CASH-REGISTERING TILL.

No. 856,294.

Specification of Letters Patent.

Patented June 11, 1907.

Application filed November 9, 1906. Serial No. 342,707.

To all whom it may concern:

Be it known that I, JOHN ALFRED PRESTWICH, of 1 Lansdowne road, Tottenham, London, England, engineer, have invented certain new and useful Improvements in Cash-Registering Tills, of which the following is a specification.

This invention relates to that type of till where the amount of the purchase is indicated by a disk having the amounts printed thereon and exhibited through a suitable window.

This invention has for its object to provide a till of this type of more efficient and simple construction.

According to this invention I employ two or more indicating disks but preferably two and the disks are so arranged by being made of different diameters that the characters of all the disks are visible on one side, while to render the characters visible on the other side also, the larger disk is perforated to render the smaller disk or disks or characters thereon visible through the larger one.

In the accompanying drawings I have illustrated one form of improved till wherein two disks are employed and I have also shown how three disks could be employed.

Figure 1 is a face view looking from the operating side with the lower part in section. Fig. 2 is a similar view looking in the opposite direction with the inclosing cover removed and partly in section. Fig. 2^a is a sectional detail. Fig. 3 is a vertical section of the machine. Fig. 4 is a sectional detail on line A—A of Fig. 3. Fig. 5 is a sectional side view on line B—B of Fig. 4. Fig. 6 is a part sectional plan on line C—C of Fig. 2. Figs. 7 and 8 show a modification wherein means are provided for indicating and recording pounds, which figures also show a device for adding the amounts of the transactions. Figs. 9 and 10 show a coin displaying device coupled to the improved cash register.

In the form shown in Figs. 1 to 6, two disks such as *a* *b* (for shillings and pence respectively) are mounted upon a common shaft and are operated directly by handles *a'* *b'* so that the disks can be rotated freely in either direction to bring the characters thereon opposite to windows *c* *c'* in the casing on each side of the apparatus. The front face of the casing or an external dial *d* over which the handles *a'* and *b'* move is marked with indicating figures as in Fig. 1 which allow the

operator to move the separate handles to the required figure and bring the corresponding character on the indicating disk to the windows *c* *c'* of the apparatus. In order that the characters may stop at the required position each handle and its corresponding disk are coupled to a notched wheel *e* *e'* respectively. The handle *a'* drives the notched wheel *e* and disk *a* mounted thereon, through an arm *f* the boss of the ratchet *e* being extended in the form of a sleeve *e'* freely mounted upon the shaft *g*. The other handle *b'* is adapted to drive the notched wheel *e'* direct through the shaft *g*, the disk *b* also being driven therefrom by a plate *f'* secured thereto and upon which the disk *b* is mounted. These notched wheels *e* *e'* are engaged by rollers *h* *h'* mounted in locking arms *j* *j'* said locking arms being suitably pivoted as at *j'* and the rollers carried thereon engage the notches in both wheels *e* *e'* so that not only is accuracy in position of the characters secured but by reason of the movement imparted to said pivoted arms *j* *j'* when the notched wheels are moved by the movement of the handles, either of the said arms through suitable connecting links *k* *k'* serve to actuate a locking catch *k* which normally locks a cash drawer such as *l* in the required position by means of a catch device *l'* thereon. A flat spring such as *k'* is provided on the underside of the catch *k* adapted to prevent "chattering" of the parts when the ratchet wheels are operated. This drawer *l* is suitably inclosed in the closed or locked position and is pressed outward when released, by a spring *l'* and for ease in working the drawer is mounted on ball races or guides such as *l*. *m* *m'* are printing wheels having raised characters upon their peripheries corresponding to the characters upon the disks *a* and *b*. The printing wheel *m* which represents the shillings column is mounted upon the extended boss *e'* of the notched wheel *e* while the other *m'* (representing the pence) is fixed upon a similar sleeve-like extension of the notched wheel *e'*. These printing rollers are suitably disposed above a recording strip *n* which is pressed there-against when the machine is operated. In the arrangement shown in the drawings an ink printing ribbon *o* is passed across the printing point between the type wheels and the record strip *n*. This record strip *n* is wound from one drum *n'* onto another *n''* and at the printing point it passes over a spring roller *p* which is carried by an

arm such as q suitably pivoted at q' and extended in the form of a bell crank downward and provided at its lower end with a pawl or arm q^2 which lies in the path of a cam r carried by the cash drawer l the arrangement being such that upon the outward movement of the drawer the cam r simply moves the pawl q^2 upon its pivot but upon the return movement the cam r engages and moves the pawl and with it the bell crank q which serves to press the spring roller p upon the printing wheels. This arm q which is returned by the spring q^3 , carries a pawl s which on the return movement after the printing operation engages and operates a ratchet wheel t attached to the drum n^2 on which the record strip n is wound, whereby the said strip is advanced one step for each operation of the till, an adjustable stop s' being provided for determining the position of the bell crank. The said bell crank arm on the return movement also engages and operates a hammer or loosely pivoted lever t' which strikes the bell t^2 . The printing ribbon o is wound at each end on suitable rollers c^1 c^2 , and means are provided for reversing the motion when one spool becomes full. For this purpose the two spools are adapted to be operated in turn by a pawl such as u which extends across between the two adjacent ratchet wheels of the rollers o^1 o^2 and can be placed in engagement either with one or the other. This automatic reversing action is obtained by means of an arm v pivotally mounted upon a reciprocating plate w and having a locking pawl v^1 . The pawl u is also pivoted upon this plate w the arm v having a slot or cut away part to allow same to swing past the pivot of the said pawl. This arm v is actuated by a roller v^2 (shown dotted) which is engaged by the ribbon when a spool is getting full. The pawl u is provided with a V-shaped extension u^1 which is adapted to rest upon one side or the other of a correspondingly shaped part v^3 of the rocking pawl v^1 . In normal operation the plate w is reciprocated vertically by means of the extension q^4 of the bell-crank lever and serves to cause the double pawl u to engage and actuate either of the spools (according to which side of its pivot the arm v is placed) while, when the spool is nearly full the roller v^2 is pressed away therefrom by the ribbon and the arm v swung over to the empty spool, and, at the same time the pawl v^1 slips to the other side of the V-shaped extension u^1 whereby the pawl u is turned on its center and caused to engage and actuate the ratchet wheel of the said empty spool, thus reversing the travel of the ribbon. The construction of the spring roller p is such as will allow a certain amount of "give" or resiliency to facilitate a clear impression being taken upon the record strip and for this purpose the roller is mounted upon a squared spindle x carried by the bell

crank arm. The boss of the roller consists of a sleeve y having disks y^1 y^2 disposed therein and the said disks are provided with elongated slots z for the reception of the spindle x , a suitable spring 2 being inserted between the upper ends of the said slots and adapted to bear upon the squared spindle. The roller formed upon the sleeve y may be of india-rubber or other suitable material.

The operation may be shortly stated to be as follows:—The handles of the disks are moved to indicate the amount of the purchase; the printing wheels are thus brought to a corresponding position. This movement by means of the notched disks releases the drawer which is pushed out by its spring, the change is given to the customer and the drawer returned to closed position. The bell-crank arm slips past the cam, advances the record strip through the pawl s and rings the bell. The printing ribbon is also advanced as above described. The amount of the purchase remains visible until the machine is again operated for the next transaction.

For the purpose of preventing any tampering of the amount indicated, I provide an indicator 3 , which is operated or released by the first movement of either of the arms which engage the notched wheels and indicates that the machine is being used and directly the figures are altered from their position the drawer is released and cannot be returned without effecting a print from the printing characters. This indicator 3 is preferably in the form of a segmental arm mounted on the same center as the disks and provided with a nose or catch 4 adapted, when the drawer is in closed position to be supported upon a ledge or part 5 of a spring pressed plate 6 , said plate being pivoted upon the same center j^2 as the locking arms j^1 . This plate 6 is provided with extensions 7 , 7 which rest against the side faces of the arms j^1 whereby, when either of the said arms are moved outward by movement of the handles a^1 or b^1 and the corresponding notched wheels, the nose 4 is released from engagement with the part 5 , and by reason of the spring 8 , the outer end of the indicator 3 is moved opposite the window 9 on each side of the machine. A stop or projection 10 on the bell crank q returns the nose 4 to engagement with the plate 6 .

When the apparatus is arranged to indicate pounds as well as shillings and pence, an extra printing wheel m^2 is mounted upon the spindle g and is provided with a handle 12 the normal position of which as will be seen in Fig. 7 is away from the aperture c' through which the amount of the purchase is exhibited. In this manner the handle does not obstruct the indication. The handle is provided with a flag like extension in the form of a quadrant 13 having the number of pounds marked thereon in such manner that when

the handle is moved the required number will appear in the window *c* and at the same time the printing wheel will be moved to bring a corresponding type to the printing center. The window *c* will be suitably elongated to show the pounds shillings and pence and the pound indicating handle may pass out through a suitable slit in the casing as at 14, Fig. 8, so as to be operated from the outside. The pounds indicator handle 12 is returned to normal position by a spring such as 50 the release being effected when the drawer is opened for the next transaction through the medium of a cam 51 on the drawer engaging a pivoted lever 52 which through the rod 53 moves the locking pawl 54 out of engagement with the teeth 55 on the snail shaped cam 17 of the pound indicator.

When the apparatus is to be fitted with an adding mechanism to show the total of the amounts indicated I provide each printing wheel with a snail like cam, which cams are shown at 15, 16 and 17 and for convenience in grouping the cam 16 is coupled to the intermediate printing wheels through the medium of a sleeve like extension thereof as at 19. Each cam is provided with suitable steps 20, 21 and 22 the number of steps corresponding to the number of pence, shillings or pounds which the respective handle indicates on the dial. Under and working against the stepped cams are disposed a corresponding number of sliding bars 23, 24 and 25 each coupled by a rack and pinion 28 through a ratchet 29 to a corresponding adding wheel of the adding mechanism 30. Each of the rods 23, 24, 25 is coupled by a spring 31 and a bell crank lever 32 to the vibrating lever *q* shown in Fig. 2 which lever *q* serves as previously described, for traveling the record ribbon.

The operation is as follows:—The several indicating handles *a*, *b* and 12 are moved to position which shows upon the window the amount of the purchase. We will assume that the amount of the purchase is £1:3:6½. In these positions the respective cams will allow their respective rods 23, 24 and 25 when operated by the bell crank *q* to pass up a distance equal to the steps on the cams which happen to be above the rods for instance the pound cam will have moved one step beyond the rod and the rod will be capable of moving up one step. The shilling cam will have moved three steps beyond the rod and the shilling rod can ascend three steps. The pence cam will have moved 13 steps beyond the rod and the pence rod will ascend 13 steps. The pence wheel will be divided into steps representing a half-penny. When the parts are in this position the money drawer is pushed back into closed position, and operates the bell cranked lever *q* as before described, and through the levers 32, the rods

23, 24, 25 are raised until stopped by the respective cams as above mentioned and by the position of the steps on the cams the movement of the rods is determined. As soon as the bell crank *q* moves back under its spring, it depresses the rods 23, 24, 25 to their original position and each rod will, through the rack and pinion 28 and ratchet and pawl mechanism 29 rotate the adding wheels a distance equal to the distance which they have ascended during their upward movement. The rods 23, 24, 25 are retained in their retired positions until the machine is again operated to indicate and record another transaction.

In order to provide for the difference of movement of each of the rods 23, 24, 25 they are connected to the levers 32 by a spring 31 of considerable flexibility and the downward movement is imparted by engagement of the lever 32 with pins 33 on the said rods.

In order that the pence wheel may add a shilling to the shilling wheel at the next operation of the shilling rod a trigger 34 is provided having a finger 35 engaged by a pin 36 on the pence wheel, said trigger is moved away from engagement with a stop 37 on the rod 24 so as to allow the said rod at the next operation to descend a distance equal to another step on the shilling cam and thereby record another shilling on the adding wheel. If this action takes place while the rod 24 is moved up, a pivoted stop 38 engages the nose of the trigger 34 and prevents it returning until after the rod 24 has descended and recorded the shilling. The stop 37 on the rod serves on the downward movement to remove the stop 38 and allow the trigger 34 to return to normal position at the next upward movement of the rod 24.

In order that the money drawer may not be closed and so make a faulty record by reason of the notched wheels *e* and *e'* and the rollers *h*, *h'* being in an intermediate position an arm *k* is mounted on the pivoted catch *k'*, and the bell crank lever *q* is provided with a stop pin *q* which comes into engagement with the end of said arms when the said parts are unlocked in the intermediate position. This engagement prevents the drawer from being pushed in and so no record is made as the bell crank lever *q* is unable to move.

It may in some cases be desirable to combine with the cash registering apparatus described a coin displaying device and one such device is shown in Figs. 9 and 10 where the coins are inserted at the top of a chute 40 made with transparent sides so as to show the coins. The coins are received upon the uppermost of two series of flaps 41 and 42 the said series being each connected by bars 43 and 44 which are alternately reciprocated by a pivoted lever 45 actuated by means of

an inclined or cam like device 46 in which runs a roller 47 mounted on the end of said lever. The cam like device 46 is mounted on the side of the drawer 1 whereby as the drawer is pulled in and out each series of flaps is alternately depressed and the coins fall from one flap to the next below at each movement of the drawer and so each coin is exhibited for a certain time before being delivered into the coin drawer above which the said coin displaying device is mounted as will be seen by Figs. 9 and 10.

What I claim and desire to secure by Letters Patent is:—

rate registering movements of the indicating disks and the type wheels, a money drawer and means for releasing same when the said notched wheels are moved, an inking ribbon disposed between the record strip and the type wheels, a bell crank lever, a cam upon the money drawer adapted to move said bell crank lever in one direction and then release same, a spring for effecting the return of said bell crank lever, means whereby the movement of the bell crank lever in one direction causes a print to be obtained from the type wheels upon the recording strip and resets the indicator controlled by the notched wheels.

7. A cash registering till having a plurality of hand operated indicating disks mounted on the same axis said disks being of different diameters the larger ones having apertures therein through which the characters on the smaller disks are visible thus enabling the characters on all the disks to be visible from both sides, type wheels one for each disk and mounted on the same axis, notched wheels one for each disk, pawls engaging said notched wheels serving to secure the accurate movement of the indicating disks and the type wheels, a money drawer and means for releasing same when the said notched wheels are moved, an indicator also released by said notched wheels, means for returning said indicator to initial position only by the closing of the money drawer, an inking ribbon, a bell crank lever, a cam upon the money drawer adapted to move said bell crank lever in one direction and then release same, a spring for effecting the return of said bell crank lever, means whereby the movement of the bell crank lever in one direction causes a print to be obtained from the type wheels upon the recording strip and resets the indicator controlled by the notched wheels.

8. A cash registering till having a plurality of hand operated indicating disks mounted on the same axis, said disks being of different diameters the larger ones having apertures therein through which the characters on the smaller disks are visible thus enabling the characters on all the disks to be visible from both sides, type wheels one for each disk, and mounted on the same axis, notched wheels one for each disk, pawls engaging said notched wheels serving to secure the accurate movement of the indicating disks and the type wheels, a money drawer and means for releasing same when the said notched wheels are moved, an inking ribbon, a bell crank lever, a cam upon the money drawer adapted to move said bell crank lever in one direction and then release same, a spring for effecting the return of said bell crank lever, means whereby the movement of the bell crank lever in one direction causes a print to be obtained from the type wheels upon the

recording strip and resets the indicator controlled by the notched wheels, two spools placed adjacent to one another upon which the opposite ends of the ink ribbon are wound, ratchet wheels on said spools, a double ratchet pawl disposed between said spools and the ratchet wheels thereon, a reciprocating plate upon which said ratchet pawl is pivotally mounted, means whereby the pressure of the ribbon when fully wound on one spool causes the double pawls to turn upon its pivot and engage the ratchet wheel of the empty spool and wind the ribbon in the reverse direction.

9. A cash registering till having a plurality of hand operated indicating disks mounted on the same axis said disks being of different diameters the larger ones having apertures therein through which the characters on the smaller disks are visible thus enabling the characters on all the disks to be visible from both sides, type wheels one for each disk and mounted on the same axis, notched wheels one for each disk, pawls engaging said notched wheels serving to secure the accurate movement of the indicating disks and type wheels, a money drawer and means for releasing same when the said notched wheels are moved, an indicator also released by said notched wheels and showing when the till is operated, means for returning said indicator to initial position only by closing of the money drawer, an inking ribbon, a bell crank lever, a cam upon the money drawer adapted to move said bell crank lever in one direction and then release same, a spring for effecting the return of said bell crank lever, means whereby the movement of the bell crank lever in one direction causes a print to be obtained from the type wheels upon the recording strip and resets the indicator controlled by the notched wheels, two spools placed adjacent to one another upon which the opposite ends of the ink ribbon are wound, ratchet wheels on said spools a double ratchet pawl disposed between said spools and the ratchet wheels thereon, a reciprocating plate upon which said ratchet pawl is pivotally mounted, means whereby the pressure of the ribbon when fully wound on one spool causes the double pawl to turn upon its pivot and engage the ratchet wheels at the empty spool and wind the ribbon in the reverse direction.

10. A cash registering till having a plurality of hand operated indicating disks mounted on the same axis, said disks being of different diameters the larger ones having apertures therein through which the characters on the smaller disks are visible thus enabling the characters on all the disks to be visible from both sides, type wheels one for each disk and mounted on the same axis, notched wheels one for each disk, pawls engaging said notched wheels to secure accurate movement of the indicating disks and the type wheels, a

money drawer and means for releasing the said money drawer when the said notched wheels are moved, an adding mechanism and means for operating said adding mechanism 5 from the indicating disks.

11. A cash registering till having a plurality of hand operated indicating disks mounted on the same axis, said disks being of different diameters the larger ones having apertures therein through which the characters on the smaller disks are visible thus enabling the characters on all the disks to be visible from both sides, type wheels one for each disk and mounted on the same axis, notched 10 wheels one for each disk, pawls engaging said notched wheels serving to secure the accurate movement of the indicating disks and the type wheels a money drawer and means for releasing the said money drawer when the 15 said notched wheels are moved, an adding mechanism and means for operating said adding mechanism from the indicating disks, cam disks one for each indicating disk and corresponding type wheel and actuated 20 therewith, said cam disks having a number of steps upon their peripheries corresponding to the fractions of each denomination of coin, an adding mechanism rods for operating said 25 adding mechanism and means for reciprocating said rods at each operation of the till, the movement of said rods being determined 30 by the position of the said stepped cams.

12. A cash registering till having a plurality of hand operated indicating disks mounted on the same axis, said disks being of different diameters the larger ones having apertures therein through which the characters on the smaller disks are visible thus enabling the characters on all the disks to be visible 35 from both sides, type wheels, one for each disk and mounted on the same axis, notched wheels one for each disk, pawls engaging said notched wheels serving to secure the accurate movement of the indicating disks and the type wheels, a money drawer and means 40 for releasing same when the said notched wheels are moved, an inking ribbon, a bell crank lever, a cam upon the money drawer adapted to move said bell crank lever in one 45 direction and then release same, a spring for effecting the return of said bell crank lever, means whereby the movement of the bell crank lever in one direction causes a print to be obtained from the type wheels upon the 50 recording strip and resets the indicator controlled by the notched wheels, cam disks, one for each indicating disk and corresponding type wheels and actuated therewith, said cam disks having a number of steps upon 55 their peripheries corresponding to the fractions of each denomination of coin, an adding mechanism, rods for operating said adding mechanism, means for operating said reciprocating rods from said bell crank lever by 60 the closing of the money drawer.

13. A cash registering till having a plurality of hand operated indicating disks mounted on the same axis said disks being of different diameters the larger ones having apertures therein through which the characters 70 on the smaller disks are visible thus enabling the characters on all the disks to be visible from both sides, means for insuring that the disks come to rest in registering position, a money drawer and means for releasing same 75 at initial movement of the indicating disks, an indicator also released by said initial movement, means for returning said indicator to initial position only by the closing of the money drawer, a bell crank lever, a cam upon the money drawer adapted to move said bell crank lever in one direction and then release same, a spring for effecting the return of the said bell crank lever, means 80 whereby the movement of the bell crank 85 lever in one direction causes a print to be obtained from the type wheels upon the recording strip and resets the said indicator, cam disks one for each indicating disk, and corresponding type wheel and actuated therewith, said cam disks having a number of steps upon their peripheries corresponding to the fractions of each denomination of coin, an adding mechanism, rods capable of being 90 reciprocated for operating said adding mechanism, means for operating said reciprocating rods from said bell crank lever by the closing of the money drawer. 95

14. A cash registering till having a plurality of hand operated indicating disks mounted on the same axis, said disks being of different diameters the larger ones having apertures therein through which the characters on the smaller disks are visible thus enabling the characters on all the disks to be visible 100 from both sides, type wheels one for each disk and mounted on the same axis, means for securing accurate movements of the indicating disks and type wheels, a money drawer and means for releasing same at the 105 initial movement of the indicating disks, an adding mechanism and means for operating same from the indicating disks, cam disks one for each indicating disk and corresponding type wheel and actuated therewith, said cam disks having a number of steps upon 110 their peripheries corresponding to the fractions of each denomination of coin, an adding mechanism rods for operating said adding mechanism, teeth upon said rods adapted 115 to engage toothed wheels mounted adjacent to the adding wheels of the adding mechanisms and adapted to drive same through ratchet and pawl connections pins upon said adding wheels, a pivoted arm engaged by 120 said pins at each complete revolution of the respective adding wheels, a step on the adjacent reciprocated rod normally engaged by said pivoted arm whereby the rod is only 125 reciprocated to the extent determined by 130

the cam until said step when released by said pivoted arm allows of an additional movement to record an additional amount equal to the sum of the pin carrying wheel which 5 releases the said pivoted arm.

15. A cash registering till having a plurality of indicating disks mounted on the same axis, said disks being of different diameters the larger ones having apertures therein through which the characters on the smaller disks are visible thus enabling the characters on all the disks to be visible from both sides, an additional indicator for high values comprising a hand operated arm carrying a flag like extension visible through windows, together with the indications on the indicator disks, means for locking said additional indicator in position to which it is moved, means for releasing said additional indicator.
20. 16. A cash registering till having a plurality of hand operated indicating disks mounted on the same axis, said disks being of different diameters the larger ones having apertures therein through which the characters 25 on the smaller disks are visible thus enabling the characters on all the disks to be visible from both sides, type wheels one for each disk and mounted on the same axis, notched wheels one for each disk, pawls engaging said 30 notched wheels serving to secure the accurate movements of the disks and type wheels, a money drawer and means for releasing same when the said notched wheels are moved, an additional indicator for high 35 values comprising a hand operated arm carrying a flag like extension visible at the indicating position, together with the indications on the indicator disks, means for locking said additional indicator in position to 40 which it is moved, means for releasing said additional indicator by the opening of the money drawer.

17. A cash registering till having a plurality of hand operated indicating disks 45 mounted on the same axis, said disks being of different diameters the larger ones having apertures therein through which the characters on the smaller disks are visible from both sides, type wheels one for each disk, pawls engaging notched wheels one for each disk, said notched wheels serving to secure the accurate 50 movements of the disks and the type wheels, a money drawer and means for releasing same when the said notched wheels are moved, an inking ribbon disposed between the record 55 strip and type wheels, a bell crank lever, a cam upon the money drawer and adapted to move said bell crank lever in one direction and then release same, a spring for effecting 60 the return of said bell crank lever, means whereby the movement of the bell crank lever in one direction causes a print to be obtained from the type wheels upon the recording strip and resets the indicator controlled 65 by the notched wheels, an additional indica-

tor for high values comprising a hand operated arm carrying a flag like extension visible at the indicating position together with the characters on the indicator disks means for locking said additional indicator in position to which it is moved, means for releasing said additional indicator.

18. A cash registering till having a plurality of hand operated indicating disks mounted on the same axis said disks being 75 of different diameters the larger ones having apertures therein through which the characters on the smaller disks are visible thus enabling the characters on all the disks to be visible from both sides, printing means coupled to each disk, pawls engaging notched wheels one for each disk, said notched wheels serving to secure the accurate movements of the indicating disks and type wheels, a money drawer and means for releasing same 80 when the said notched wheels are moved, an indicator showing when the till is operated and also released by the initial movement of said notched wheels, means for returning said indicator to initial position only by the 85 closing of the money drawer, a bell crank lever, a cam upon the money drawer adapted to move said bell crank lever in one direction and then release same, a spring for effecting the return of said bell crank lever, means 90 whereby the movement of the bell crank lever in one direction causes a record to be printed on the recording strip and resets the indicator controlled by the notched wheels, an additional indicator for high values comprising a hand operated arm carrying a flag like extension visible at the indicating position together with the characters on the indicator disks, means for locking said additional indicator in position to which it is moved 95 means for releasing said additional indicator by the opening of the money drawer.

19. A cash registering till having a plurality of hand operated indicating disks mounted on the same axis, said disks being 100 of different diameters the larger ones having apertures therein through which the characters on the smaller disks are visible thus enabling the characters on all the disks to be visible from both sides, printing means coupled to said indicator disks, notched wheels one for each disk, pawls engaging said notched wheels serving to secure the accurate movements of the indicator disks, a money drawer and means for releasing same when the said 105 notched wheels are moved, an indicator shown when the till is operated and also released by said notched wheels, means for returning said indicator to initial position only by the closing of the money drawer, a bell 110 crank lever, a cam upon the money drawer adapted to move said bell crank lever in one direction and then release same, a spring for effecting the return of said bell crank lever, means whereby the movement of the bell 115

8
crank lever in one direction causes a print to be obtained upon the recording strip and releases the indicator controlled by the notched wheels, an additional indicator for high values comprising a hand operated arm carrying a flag like extension visible at the indicating position together with the characters on the indicator disks, means for locking said additional indicator in position to which it is moved, means for releasing said additional indicator by the opening of the money drawer, cam disks one for each indicating disk and actuated therewith, said cam disks having a number of steps upon their peripheries corresponding to the fractions of each denomina-

tion of coin, an adding mechanism, rods for operating said adding mechanism and means for reciprocating said rods at each operation of the cash register, the movement of said rods being determined by the position of the said stepped cams, means for operating said reciprocating rods from said bell crank lever by the closing of the money drawer.

In witness whereof, I have hereunto signed my name in the presence of two subscribing witnesses.

JOHN ALFRED PRESTWICH.
